UNITED STATES PATENT OFFICE.

DUKE F. BAXTER, OF ROCHESTER, NEW YORK, ASSIGNOR OF ONE-FOURTH
TO FRANCES A. BAXTER, OF SAME PLACE.

BUTTON OR STUD FASTENER.

SPECIFICATION forming part of Letters Patent No. 293,301, dated February 12, 1884.

Application filed November 26, 1883. (No model.)

To all whom it may concern:

Be it known that I, DUKE F. BAXTER, a citizen of the United States, and a resident of the city of Rochester, Monroe county, State of New York, have invented new and useful Improvements in Button and Stud Fasteners, of which the following is a specification.

My invention relates to that class of buttons, studs, clasps, &c., in which a threaded stem passed through a fabric is the means of securing thereto a button, stud, or other attachment; and my invention consists in constructing the attachment, as fully described hereinafter, so that the stem may be easily passed through the fabric without injury to the latter.

In the drawings, Figure 1 is a sectional view, enlarged, showing my attachment as applied to securing a button to a fabric. Fig. 2 is an external view of a modification. Fig. 3 is a plan of the stem. Fig. 4 is a section showing the attachment as used in securing the ornamental pendant of a leather or heavy fabric hanging.

Heretofore it has been common to make studs in two parts, one being the button, and the other a headed screw-pin passing through the fabric into the button. It is not practicable to force the threaded stems of such attachments directly through heavy fabrics, and it is common to perforate the latter with a piercer, or to use a hollow-ended needle to facilitate the introduction of the stem. To avoid the use of these secondary appliances, which tear and otherwise injure the fabric, and which cannot sometimes be obtained, I make the stem *a* with the usual cylindrical body having a screw-thread adapted to that in the body *A* of the button or other device, and extend the stem beyond the body to form a tapering gimlet-pointed end, in which I form one or more quick screw-threads, *c*, having a greater pitch than the screw-thread upon the body of

the stem, Fig. 1 showing a termination with two threads, and Fig. 2 a termination with a single thread.

A stem having a tapering point may be passed through the fabric without the use of piercers or needles; but has more or less tendency to separate and tear the finer fibers. If, however, the tapering point has a quick screw-thread, or a thread having a comparatively large pitch, it will enter the fabric freely and without injury thereto, so that the position of a stud or button may be repeatedly changed within a limited space without injury to the fabric. The reason of this will be apparent upon inspecting Fig. 3, from which it will be seen that the cross-sectional dimensions of a threaded stem are much less than of a solid one, thereby lessening the spread of the fibers where the penetration occurs. To facilitate the passage of the screw-stem into the fabric, I provide said stem with a head having projecting arms *i*, whereby it may be readily turned.

Without limiting myself to any special form of stud or button, I claim—

1. A detachable stud consisting of a head having a threaded opening and a stem having a threaded body terminating at one end in a head and at the other in a tapering gimlet-point having one or more quick screw-threads, substantially as set forth.
2. The combination of the button or stud and the attachment having a screw-stem and lateral arms at the outer ends, for the purpose set forth.

In testimony whereof I have signed my name to this specification in the presence of two subscribing witnesses.

DUKE F. BAXTER.
